POSTAGE STAMP SEALER OR THE LIKE

Thomas P. O'Donnell, Kings County, N.Y.
(220 Highland Blvd., Brooklyn, N.Y. 11207)

Filed Feb. 2, 1968, Ser. No. 10,416

Term of patent 14 years

Int. Cl. D19—02

U.S. Cl. D74—1

FIG. 1 is a perspective view of a postage stamp sealer showing my new design;

FIG. 2 is another embodiment of the postage stamp sealer shown in FIG. 1 wherein the handle portion tapers inwardly towards the top; and

FIG. 3 is a further embodiment of the postage stamp sealer shown in FIG. 1 wherein the handle portion has been angled so that same is octagonal in cross section.

The sides opposite to those shown in FIGS. 1, 2 and 3 present a similar appearance as the sides disclosed.

I claim:

The ornamental design for a postage stamp sealer or the like, as shown and described.
